CONTROL APPARATUS

Bernard E. O'Hagan, Swissvale, Pa., assignor to
The Union Switch & Signal Company, Swiss-
vale, Pa., a corporation of Pennsylvania

Application June 28, 1938, Serial No. 216,248

6 Claims. (Cl. 246—107)

My invention relates to control apparatus, and is particularly well adapted for, but not limited to, controlling a device for recording the presence of vehicles upon a selected stretch of trackway.

An object of my invention is the provision of novel and improved means to control a device for recording the progress of vehicles along a stretch of trackway whereby the speed of such vehicles may be accurately determined and recorded. Other objects and advantages of my invention will appear as the specification progresses.

I shall describe two forms of apparatus embodying my invention, and shall then point out the novel features thereof in claims.

In the accompanying drawing, Fig. 1 is a dia-
grammatic view showing one form of apparatus
embodiment my invention when applied to meas-
uring the speed of trains. Fig. 2 is a dia-
grammatic view showing a modified form of the appa-
ratus shown in Fig. 1 and also embodying my
invention. Fig. 3 is a view, partially dia-
grammatic, of a form of recording device that may
be used with my invention.

Similar reference characters refer to similar parts in each of the several views.

Referring to Fig. 1, the reference characters 1 and 1a designate the track rails of a stretch 30 of railway track X over which traffic normally moves in a direction shown by an arrow. Located at selected points along track X are track instruments designated by the reference characters M¹ and M², so disposed as to be actuated by trains passing along track X. Track instruments M¹ and M² are preferably of the same form, and may be any one of the well-known types of track instruments provided with a normally closed contact which is operated to an open position in response to a passing train, such as, for example, the microphone type covered by United States Letters Patent 1,834,077 issued to A. J. Sorensen on December 1, 1931, or the mercury contact type covered by United States Letters Patent 2,076,928 issued to H. G. Witmer on April 13, 1937. Track instrument M² is preferably spaced a known distance from track instrument M¹.

A normally energized stick relay R¹ is associated with track instrument M¹, and is provided with a pick-up circuit passing from terminal B of a suitable source of current, such as a battery not shown, through instrument M¹, the winding of relay R¹ and front contact 2 of a relay SR, to be referred to later, to terminal C

of the current source; and with a stick circuit passing from terminal B through instrument M¹, the winding of relay R¹ and front contact 3 of relay R¹ to terminal C. Relay SR, referred to previously, is energized over a simple circuit including back contact 4 of relay R¹, and preferably, relay SR is provided with slow releasing characteristics effected in part by a condenser 21 connected across the winding of the relay. Relay SR is also preferably provided with slightly slow pick-up characteristics.

A normally deenergized control relay R² is associated with instrument M², and is provided with a pick-up circuit passing from terminal B through instrument M², the winding of relay R², back contact 5 of relay SR, and back contact 6 of relay R¹ to terminal C; and with a stick circuit passing from terminal B through instrument M², the winding of relay R² and front contact 7 of relay R² to terminal C.

The reference character RD indicates an electroresponsive device controlled by relay R². While any desired type of electroresponsive device may be controlled by relay R², in the particular embodiment of my invention chosen to serve as an illustration, the device RD is any one form of the usual and well-known types of recording devices capable of indicating and recording the period of time during which the device is energized. One form that recording device RD may take is shown in Fig. 3. Referring to Fig. 3, device RD as herein shown is provided with a tape 9 passing over rolls 10, 10. Tape 9 is unwound from a roll 11 onto a roll 12 by means of a suitable mechanism, shown here as a motor 13 connected with roll 12 by a train of gears 14. Tape 9 is preferably provided with time divisions 15 corresponding to the rate at which the tape is moved by motor 13. Recorder RD is further provided with a magnet 16, and a pivotally mounted member 17 biased by any suitable means such as, for example, a spring 18 to a position away from the magnet. Rigidly attached to member 17 is a stylus 19 which may, for example, be a pencil, and which pencil is adapted to trace a record on tape 9. The magnet 16 and member 17 are so disposed that the pencil 19 is moved transversely across tape 9 toward the magnet when the magnet is energized and away from the magnet to a normal position, as shown in the drawing, when the magnet is deenergized. As shown herein, magnet 16 is energized in multiple with motor 13, so that when magnet 16 is energized to attract stylus 19, motor 13 is also energized to wind tape 9 upon

roll 12 whereby tape 9 is moved continuously past stylus 19 during the period that recording device RD is energized, device RD being energized over a circuit passing from terminal B through front contact 8 of relay R2, wire 22, and recorder RD to terminal C. It should be noted that stylus 19 traces a straight line on tape 9 during the period that recorder RD is energized; and that the length of line traced by stylus 19 for any period of energization of recorder RD is defined by the transverse motion of stylus 19 across tape 9 at the start and termination of each period of energization of the recorder.

Having thus described various parts of apparatus of Fig. 1, I shall now explain their operation. I shall first assume that the apparatus is in its normal condition, as shown in Fig. 1. In this normal condition of the apparatus, that is to say, when no train is upon track X so that track instruments M1 and M2 are not actuated, relay R1 is energized, relays R2 and SR are de-energized, and recording device RD is also de-energized.

I shall now assume that a train, moving in the direction of normal traffic along track X reaches the location of instrument M1. The actuation of that instrument opens the previously traced stick circuit for relay R1 with the result that relay R1 releases, thereby opening front contact 3 and closing back contacts 4 and 6. The closing of back contact 4 of relay R1 completes the simple energizing circuit for relay SR. With relay R1 released, closing back contact 6, and before relay SR picks up opening back contact 5, the previously traced pick-up circuit for relay R2 is completed so that relay R2 becomes energized to close front contacts 7 and 8. When contact 7 closes, the previously traced stick circuit for relay R2 is completed, and when contact 8 of relay R2 closes, recording device RD becomes energized so that magnet 16 attracts stylus 19, and motor 13 actuates roll 12 with the result that tape 9 is wound on roll 12, and is moved past stylus 19. Relay R2 is held energized by virtue of its stick circuit (the pick-up circuit for relay R2 being opened when back contact 5 of relay SR opens upon the picking up of relay SR) until the train reaches the location of track instrument M2, and during this time interval, recorder RD is energized so that stylus 19 traces a straight line on tape 9. The actuation of instrument M2 opens the stick circuit for relay R2 with the result that relay R2 becomes released to open front contacts 7 and 8, the opening of the latter opening the energizing circuit for recorder RD so that magnet 16 becomes de-energized and permits stylus 19 to return to its original position by virtue of its spring bias, and motor 13 becomes deenergized to terminate the movement of tape 9. It can be seen that stylus 19 records on tape 9 the interval of time between a train actuating instrument M1 and instrument M2, and the length of line traced by stylus 19 records the period of energization of recorder RD. It follows that since the distance between instruments M1 and M2 is known, the rate of speed of the train along track X may be readily and accurately determined.

When the train completely passes instrument M1, relay R1 becomes energized over its pick-up circuit, and relay SR becomes deenergized. Then, when the train completely passes instrument M2, the apparatus is restored to its normal condition.

It should be noted that relay SR is preferably

provided with slow releasing characteristics, so that a second operation of recorder RD will not be effected in the event a slow moving train is positioned along track X so as to actuate both track instruments M1 and M2 simultaneously. 5 Relay SR is preferably provided with slow releasing characteristics of an order longer than the intervals between the actuation of instrument M1 by the successive wheels of a slow moving train, so that an intermittent actuation of 10 instruments M1 and M2 due to a very slow passage of a train along track X which may cause only intermittent energization of relay SR, does not result in the release of relay SR and the reestablishment of the pick-up circuit for relay 15 R2.

Referring now to Fig. 2, the apparatus of Fig. 2 is the same as the apparatus of Fig. 1 except that a slow pick-up relay SP is added, relay SP being energized over a simple circuit including 20 back contact 4 of relay R1, and the pick-up circuit for relay R1 being carried over a front contact of relay SP; the pick-up circuit for relay R1 passing from terminal B through instrument M1, the winding of relay R1, and front contact 25 20 of relay SP to terminal C.

It is obvious that the addition of relay SP does not alter the operation of the recorder RD as described in detail in connection with Fig. 1, relay SP being added to further insure that double 30 operation of recorder RD is not effected by a single train. It can be seen that a train, actuating instruments M1 and M2 intermittently due to a very slow passage along track X, will not cause a double operation of device RD since relay R1 once released cannot be reenergized until relay SP picks up at the end of its slow pick-up period and relay SR is not deenergized until relay R1 is picked up. Thus the slow pick-up period of relay SP is added to the slow release 40 period of relay SR before the pick-up circuit for relay R2 is completed with the result that a second operation of recorder RD because of intermittent operation of track instruments M1 and M2 is a remote possibility.

It is to be understood, of course, that while herein described, apparatus embodying my invention is employed for controlling a device for recording the progress of trains along a railway track, the scope of my invention is in no 50 way restricted to recording devices; and that the scope of my invention embraces the control of any suitable electroresponsive device.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a stretch of railway track provided with a first and a second track instrument each having a normally closed contact operable to an open position in response to a passing train, a first relay, a slow releasing relay, a pick-up circuit for said first relay serially including the contact of said first track instrument and a front contact of said slow releasing relay, a stick circuit for said first relay including the contact of said first track instrument, an energizing circuit for said slow releasing relay including a back contact of said first relay, a control relay, a pick-up circuit for said control 75

relay serially including the contact of said second track instrument, a back contact of said slow releasing relay, and a back contact of said first relay; a stick circuit for said control relay including the contact of said second track instrument, and a control circuit including a front contact of said control relay.

2. Apparatus for recording the arrival of trains at selected points along a stretch of railway comprising, in combination, a stretch of railway track provided with a first track instrument located at a first selected point along said stretch and a second track instrument located at a second selected point along said stretch, each said track instrument having a normally closed contact operable to an open position in response to a passing train, a slow releasing relay, a first stick relay, an energizing circuit for said slow releasing relay including a back contact of said first stick relay, a pick-up circuit for said first stick relay serially including the contact of said first track instrument and a front contact of said slow releasing relay, a stick circuit for said first stick relay including the contact of said first track instrument, a second stick relay; a pick-up circuit for said second stick relay serially including the contact of said second track instrument, a back contact of said slow releasing relay and a back contact of said first stick relay; a stick circuit for said second stick relay including the contact of said second track instrument, a recording device, and an energizing circuit for said device including a front contact of said second stick relay.

3. Apparatus for recording the arrival of trains at selected points along a stretch of railway track comprising, in combination, a stretch of railway track provided with a first track instrument located at a first selected point along said stretch and a second track instrument located at a second selected point along said stretch and each track instrument having a normally closed contact operable to an open position in response to a passing train, a slow pick-up relay, a first stick relay, an energizing circuit for said slow pick-up relay including a back contact of said first stick relay, a pick-up circuit for said first stick relay serially including the contact of said first track instrument and a front contact of said slow pick-up relay, a stick circuit for said first stick relay including the contact of said first track instrument, a slow releasing relay, an energizing circuit for said slow releasing relay including a back contact of said first stick relay, a second stick relay; a pick-up circuit for said second stick relay serially including the contact of said second track instrument, a back contact of said slow releasing relay and a back contact of said first stick relay;

a stick circuit for said second stick relay including the contact of said second track instrument, a recording device, and an energizing circuit for said device governed by said second stick relay.

4. In combination, a stretch of railway track provided with a first and a second track instrument, said track instruments located spaced apart along said stretch and each having a normally closed contact operable to an open position in response to actuation by a train, a first relay, an energizing circuit for said first relay including the contact of said first track instrument, a slow acting relay, an energizing circuit for said slow acting relay controlled by a back contact of said first relay, a control relay, a pick-up circuit for said control relay controlled jointly by the contact of said second track instrument and by a back contact of said slow acting relay, a stick circuit for said control relay controlled by the contact of said second track instrument, and a circuit governed by said control relay for energizing an electroresponsive device.

5. In combination, a stretch of railway track provided with a first and a second track instrument each having a normally closed contact operable to an open position in response to a passing train, a first relay energized over a circuit including the contact of said first track instrument, a slow releasing relay energized over a circuit including a back contact of said first relay, a control relay; a pick-up circuit for said control relay serially including the contact of said second track instrument, a back contact of said slow releasing relay, and a back contact of said first relay; a stick circuit for said control relay including the contact of said second track instrument, and a control circuit governed by said control relay.

6. In combination, a stretch of railway track over which traffic normally operates in a given direction, a first and a second track instrument located at spaced points along said stretch and each instrument being provided with a normally closed contact which is operated to an open position in response to passing trains, said instruments being so located that said first instrument is actuated by trains operating in the given direction over said stretch prior to said second instrument being actuated, a first relay normally energized over a circuit including the contact of said first instrument, a second relay provided with a pick-up and a stick circuit each being governed by the contact of said second instrument, means governed by said first relay for momentarily establishing said pick-up circuit for said second relay when said first instrument is actuated by a train, and a control circuit for an electroresponsive device governed by said second relay.

BERNARD E. O'HAGAN.
